CONTAINER

Max G. Biberthaler, Meriden, Conn., assignor of
one-half to Wesley R. Becher, Wethersfield,
Conn.

Application January 31, 1939, Serial No. 253,758

4 Claims. (Cl. 229—39)

My invention relates to containers of the knock-down type and particularly to such containers or cartons as are made from corrugated board which commonly consists of a corrugated sheet of paper material between two flat sheets of a similar material.

Heretofore, cartons of this type have been produced which required the use of a strip of adhesive tape to keep them closed. In other types of such cartons, means have been provided for locking the flaps thereof in closed position. No provision, however, has heretofore been made whereby the flaps of the carton may be locked in closed position, without the use of additional sealing means, and so that they could be unlocked without damaging any part of the carton, or the sealing means, to permit re-use of the carton after it has been opened.

An object of my invention, therefore, is to provide self-locking means, for the end flaps of such cartons, whereby the said flaps may be locked in position without requiring the use of additional sealing means.

A further object of my invention is to provide a carton having improved locking means and which is formed from a blank that is so constructed that the same may be produced in a most economical manner through the elimination of waste in the cutting of said blank from a sheet of material.

My invention further provides other novel features and advantages which are obtained by details of construction having considerable utility and which appear more fully in the following description and from the accompanying drawing in which:

Figure 1 is a plan view of a carton blank embodying my invention.

Figure 2 is a perspective view, on an enlarged scale, illustrating a carton formed from such blank.

Figure 3 is a fragmentary view, in central vertical section and on a further enlarged scale, through a portion of my improved carton showing the flaps thereof closed and in locked position.

Figure 4 is a fragmentary plan view, in elevation, and on a still further enlarged scale, illustrating a portion of the end flap of the carton comprising my improved locking means.

Figure 5 is a front view, in elevation, of the said locking means.

Figure 6 is a plan view showing a modified form of a carton blank comprising my invention.

Figure 7 is a similar view showing such a blank in a further modified form.

Figure 8 is a plan view of a blank for the end flaps used in connection with the blank shown in Figure 7.

Figure 9 is a perspective view of a carton, formed from the blank illustrated in Figure 7, with one of the end flaps shown detached therefrom.

As illustrated in Figure 1 of the drawing, my invention provides for a carton blank which consists of side wall portions 5, 6 and 7; The said portions 5 and 6 being provided with extensions forming flaps 8 and 9, which are adapted to be folded on the dotted lines 10, and the portion 7 being provided with extensions forming the flaps 11 which are adapted to be folded on the dotted lines 12.

In order to produce the said blank in a most economical manner by reducing to a minimum the amount of waste resulting from the cutting of said blank, I provide a separate piece comprising a wall portion 13 having extensions forming the end flaps 14 which are foldable on the dotted lines 15. The said separate piece may be joined to the remainder of the blank by means of the flaps 16 and 17 which extend from the side wall portions 5 and 6 thereof and are secured to the said separate piece, as indicated at 18, by suitable fasteners. The said flaps 16 and 17 and side portions 5, 6 and 7, being foldable on dotted lines 19, 20, 21 and 22.

Previous to folding the said blank into a carton, the same is folded over and the flap 16 is secured to the portion 13, at 23, in the same manner as the flap 17 is secured by means of the fastener indicated at 18.

It will be noted that the end flaps 14 extend for the full distance across the end of the carton and that they may be provided in a blank formed from a single piece of material as illustrated in Figure 6 of the drawing. However, cutting such a blank will cause considerable waste of material for the reason that the said end flaps 14 extend beyond the other portions of the blank and, therefore, necessitate the use of a larger sheet of material than is required to produce the blank illustrated in Figure 1 wherein a separate piece is used to provide the end flaps 14.

In addition to providing maximum economy in the production of a blank for a carton, I, by my invention, provide means whereby the said end flaps may be locked, in position to keep the carton closed, by a simple operation and

without requiring the use of additional sealing means. Furthermore, my invention provides for permitting a carton to be opened without destroying the locking means so that the said carton may be re-used after it has been opened for inspection of the contents thereof or to remove the said contents therefrom. This is a particular advantage where such cartons are especially designed to contain certain goods which are transported to stores where it may be desired to remove said goods from the cartons, for inspection or for the purpose of displaying them, and then return the goods to the same carton.

My improved sealing means comprises opposed extensions 24, on the end flaps 14, having outwardly diverging opposed edges 25 terminating in notches 28 against the edge 27 of the end flaps to provide hooks 28 in each of said extensions. The flaps 11, which extend from the wall portion 7, that is opposite the wall portion 13, are provided with notches or slits 29, adjacent the folding lines 12, to receive the extension 24 therein as will now be described.

In forming the carton, as illustrated in Figure 2, the blank illustrated in Figure 1 is first folded on the lines 19, 20, 21 and 22 and the flap 16 is joined, by the fastening means 18, to the side, indicated at 23, of the wall portion 13. Then the flaps 11 are first folded inwardly on the lines 12 in the partly folded blank and the flaps 8 and 9 are turned inwardly over the said flaps 11 as clearly illustrated in Figure 2. When the said flaps are in this position, the end flaps 14 are folded, on the lines 15, over the flaps 8, 9 and 11, and the extensions 24 are folded on lines 30 and inserted in the notches 29 over the edges of the flaps 8 and 9 which are narrower than the wall portions 5 and 6 to expose said notches. The end flaps are then simply forced downwardly on the carton and thereby causing said extensions 24 to enter the carton through the slots 29 and the hooks 28 to lock under the flaps 11, as clearly illustrated in Figure 3 of the drawing; thus locking the said end flaps over the flaps 8, 9 and 11 and securely retaining the said flaps in locked position to prevent accidental opening of the carton.

As clearly illustrated in Figures 4 and 5, it will be noted that the hooks 28 extend in a cross-wise direction to the corrugations of the corrugated sheet 31 in the material from which the blank is cut. This renders the hook portions flexible in that direction and provides advantages of considerable utility since it permits the said hooks to compress, by contact with the ends 32 of the notches 29, as the extensions 24 are being forced into said notches, and then spring back towards their original shape and cause the hooks to lock under the said ends and flaps 11. Furthermore, the ends 32 of the notches are disposed parallel to the corrugations 31 to permit the blank material, at those points, to also compress, by contact with the diverging edges 25 of the hooks 28, and then return to its normal condition and into said hooks to be retained therein.

By reason of the flexibility thus rendered to my improved locking means, the same may be used several times without seriously effecting the locking action of the hooks with relation to the edges of the notches 29. This will permit the locking means to remain effective for securely holding the end flaps 14 in locked position so that the carton may be re-used with all the advantages provided by said locking means.

In the modification illustrated in Figure 6, it will be noted that the end flaps 14 are disposed in a

different position from that of the end flaps in the blank illustrated in Figure 1. My improved locking means, however, are fully effective on a blank of this form although the blank itself is more costly to produce, on account of the extra waste of material, than when the said blank is made from two pieces as the one illustrated in Figure 1.

In the modification illustrated in Figure 7, I provide a blank which is also very economical to produce for the reason that the end flaps for said blank are formed as separate pieces 14-b having the extensions 24-b which are foldable on the dotted lines 28-b and are provided with hooks 28-b. On this form of a blank, both of the wall portions 7-b and 13-b are provided with flaps 11-b which are notched, as at 28-b, to receive the extensions 24-b.

In forming a carton from the said blank, the same is folded on the dotted lines 18-b, 28-b and 21-b and the edges of the blank are joined by a strip of adhesive, indicated at 33. The flaps 11-b are then folded inwardly and the flaps 8-b and 9-b are folded over them; thus closing the end of the carton, as clearly illustrated in Figure 9 of the drawing. The end member 14-b is then folded, with the extensions projecting laterally therefrom, and the said extensions are inserted through the notches 18-b. The hooks 28-b will then engage under the flaps 11-b thus locking the said end member in position, over the other flaps, and retaining the said flaps and carton in locked position.

From the foregoing specification, it will be clearly understood that I have provided a blank for a carton which can be produced with a minimum of waste and which includes economical and efficient locking means whereby the said carton may be locked in closed position. The said locking means being adapted for use on blanks of various sizes and forms and so constructed as to provide a degree of resiliency in the locking portions thereof which will permit re-use of the carton for the purposes above set out.

I claim:

1. A carton comprising side walls each having a flap extending inwardly on said carton with the edge thereof substantially in abutment with the edge of an opposite flap, two of said flaps overlying the other flaps to form at least a double layer of flaps closing an end of said carton, the underlying flaps having notches extending inwardly from the edges thereof adjacent the side walls of said carton, a separate cover having extensions at the sides thereof in alignment with opposite edges of said end, and hook portions on said extension adapted to engage the said lower flaps adjacent the notches therein and to lock said cover over the overlying flaps and thereby retain said flaps in closing position and provide at least three layers of the material of said carton extending entirely over the area of the ends thereof.

2. A carton comprising side walls each having a flap extending therefrom and bent inwardly over the end of said carton, two of said flaps closing the end of said carton with their edges substantially in abutment, the other flaps also closing the end of said carton and overlying the first two flaps with the edges thereof substantially in abutment, the lower flaps having notches extending inwardly from the side edges thereof, a separate cover having extensions at the corners thereof in alignment with opposite edges of said end and insertible in said notches, and hook portions on said extensions for engaging the said lower flap portions

adjacent the ends of said notches to retain said cover in locked position over said overlying flaps with the corners of said cover securely retained against the end of said carton.

3. A carton comprising side and end walls each having a flap extending inwardly on said carton, two of said flaps overlying the other flaps over an end of said carton, the underlying flaps having notches extending inwardly from the edges thereof adjacent the walls of said carton, a cover having extensions on the edges thereof and registering with said notches, and opposed hook portions in said extensions for engaging the surface of said underlying flaps adjacent the ends of the notches therein and thereby locking said flaps in relative 15 position and closing said carton.

4. A carton of the character described comprising side walls each having a flap extending inwardly on said carton, two of said flaps overlying the other flaps at an end of said carton, a separate cover overlying all of said flaps, extensions on the edges of said cover adjacent corners thereof, at least one of the underlying flaps having notches extending inwardly from the edges thereof and disposed to receive said extensions, and hook portions on said extensions adapted to project beyond the ends of said notches and engage the underlying flap for retaining the upper flaps in position relative to the lower flap and closing said carton.

MAX G. BIBERTHALER.
